SHOETREE AND RACK

Hugh R. MacMichael, Piedmont, Calif.

Application March 19, 1936, Serial No. 69,679

14 Claims. (Cl. 12—128)

This invention relates to shoe trees and a supporting rack usable in combination therewith.

Some of the objects of this invention may be noted as the following: to provide a shoetree and rack combination whereon a shoe may be treed with substantially as little effort as would be required to place it upon a shelf; and to provide said combination adapted for firmly attaching to a wall or other means of support, and thereafter adapted for use with substantially no manual handling or direct manipulation of any part of said combination for the treeing on or removal therefrom of a shoe.

Other objects are: to provide a tree which will subject said treed shoe only to light adjustable transverse stresses effective to straighten it and smooth out the vamp by pressures applied generally perpendicularly against the toe insole, vamp, and shank of said shoe; to effect said treeing stresses substantially free of harmful lengthwise stretching effect in the treed shoe which latter is frequently observed with the use of shoe trees most commonly used heretofore; to provide a tree with resilient and very flexible characteristics adapting it for effective harmless use, generally with any shoe of an individual's set of shoes; and to provide simple means of adjusting the form and resilient characteristics of said tree adapting it to an effective harmless use for a still greater range in form and character of shoes usable therewith.

Another object is to provide an effective, shoe-straightening tree usable in detached form which, by one hand, may easily be pushed directly into a shoe held in the other hand, said operation being devoid of the hitherto common necessity of thereafter having to flex and insert a powerful spring-supported or toggle-jointed member.

Other objects are to provide the aforesaid advantageous characteristics in said tree and rack in a design having very few parts, each and all suitable for quantity production, light in weight and low in cost. Other advantages will become apparent.

Illustrating my invention are the drawings herewith in which

Fig. 1 is a front elevation of a shoetree and one end of its supporting rack;

Fig. 2 is an enlarged cross-section taken on the line 2—2 of Fig. 1 and showing also a treed shoe in cross-section;

Fig. 3 is a rear elevation of the shoetree of Fig. 1;

Fig. 4 is a side elevation of the shoetree omitting the supporting rack, showing the shank

spring in varying flexed positions, and having added a shank adjusting member;

Fig. 5 is an end view taken on the line 5—5 of Fig. 4;

Fig. 6 is a side elevation of another mode of making the tree and rack combination; and

Fig. 7 is a front elevation of the shoetree of Fig. 6.

Referring to the drawings, a shoetree 20 (see Figs. 1, 2, and 3) has a toe piece 21 provided with the vamp contact surface 22, the toe insole contact surface 23 and the rear end surface 24, said toe piece 21 preferably being made of wood. A shank piece 26 is made preferably of flexible steel spring strip adapted to flex freely and resiliently into the general form of a loop having its end 27 secured in a long rectangular slot 28 entering through said toe piece rear end 24, there to be retained by the barb 29 formed by shearing laterally a short distance into the side of said shank end 27 and deflecting the inner sheared resilient part slightly upwards to form said barb 29 adapted to be forced into said slot 28 but fish-hook fashion resisting withdrawal therefrom. The other end of said flexible shank 26 is brought around and held preferably in the slot 30 entering the bottom of said toe piece 21, or in the slot 31 entering likewise at a differing angle and spaced lengthwise in said toe piece 21 from said first slot. Said shank 26 is thus caused to form a generally oval shaped resilient loop with its lower rearward part 32 adapted to contact against the shank of a treed shoe. Said slots 30 and 31 are of a size adapted to receive said shank 26 with the slight hook-like bend 33 by inserting the latter at a favorable angle therein. This bend 33 forms a catch resisting withdrawal by direct backward pull such as is exerted when the tree is being inserted into a shoe, and the inside end of said slot 30 or 31 resists forward movement thereof.

Also fixed in said toe piece rear end 24 underlying said shank fixed end 27 is the short strip retainer spring 35 (see Fig. 2) and the socket shank 36 integral with the rectangular socket 37 adapted to engage removably with the supporting arm 40, carried in spaced position along the rack beam 41 non-rotatably carried by the wall bracket 42 from a supporting means wall 43. Said socket 37 encases said retained spring 35, the tree shank 26, the upper end of the arm 40, and the longitudinally triangular space 39, and is provided with the integral bent-down latch 45 to engage in the supporting arm notch 44. Said arm 40 has the tapering end 40a adapted to enter

between said socket latch 45, and said spaced underlying shank 26. When said entering arm 40 reaches its socketed position adjacent said toe piece end 24, said retainer spring 35 forces said 5 arm notch 44 into removable retaining engagement with said socket latch 45. Said socket shank 36 is provided with the upturned end 48 engaging behind said barbed shank end 27 thereby to be forcibly retained in said toe piece slot 10 28, said retainer spring 35 being frictionally retained in said slot between said shank end 27 and said socket shank 36.

Said vamp surface 22 of said toe piece 21 forms generally a semi-conical frustum adapted to make 15 generally parallel contact inside the vamp of a treed shoe, thereby tending to smooth out wrinkles in the latter.

Said toe piece bottom 23 is adapted to make a longitudinally curved contact at about 23a 20 against the toe insole of a treed shoe, and is especially adapted to glide easily, sled-runner fashion, relative to a shoe being placed upon or removed from said tree.

Said shoetree and rack combination may be 25 produced in another mode as shown in Figs. 6 and 7 wherein an arm or body member 70 extends upwardly and inwardly from its supporting rack bar 71, and is provided on the inner side near its enlarged upper end 70a with the toe 30 insole contact 72, and spaced backward therefrom on the opposite side is the vamp contact 73. Attached to said member 70 is the shank contact 75 flexibly adaptable to contacting in the shank of a treed shoe.

35 Said shank 75 may be attached at its upper end by the screw 76 on said body toe insole part 72, therefrom being flexed to a loop form, with said shank 75 other end attached by screw 77 at the screw-hole 78 or alternatively at the screw-hole 79 relatively spaced longitudinally generally in the middle section of said body 70. Other modes of attaching said shank 75 to said body 40 70 may be used, such for example as the bent shank end removably engaging in one of one or more slots (see slots 39 and 31 of Fig. 2), or the lower end of said shank 75 might be fixed to a movable mounting encasing said body 70 in its narrow part and slideable for adjustable position longitudinally thereon. Other variations will 45 occur readily to one skilled in mechanical design, generally providing for the objects herein set forth.

50 A resilient reinforcing member 90 (see Figs 4 and 5) has the flexible longitudinally extending strip spring 91 fixed at its center in the slide 92 slidably encasing said shank 26. Said member 90 may be slid along to any position on said shank, and when said spring 91 is in any flexing position it then reinforces the resilient flexed 55 shank 26. For example, as shown in Fig. 4 said spring 91 is but slightly flexed and consequently exerts but little reinforcing effect. But if it is moved to the position indicated by the dotted lines 60 93 in a sharply curved flexed part of said shank 26, a maximum of reinforcing stiffening effect will there be exerted. Said member 90 is enabled 65 therefore to provide an adjustment in the resilient force and form of said shank 26 thereby increasing its adaptability for use with shoes 70 widely varying in form, size or weight. It may be used also in the same general mode with the shank 75 (see Fig. 6) but is not thereon shown.

75 The shoetree may be used unattached to a rack (see Figs. 4 and 5). Holding the shoe in one hand, the tree is handled by the rear end of the

loop shank and a simple continuous pushing motion serves to insert it in said shoe. The general reverse of the aforesaid motion serves to remove the tree with equal facility. Adapting it to a very wide range of sizes and forms of shoes are the adjustable features of said tree which may be provided by the variably positioned spring adjuster 90, or by the alternative slots 39 and 31 adapted to variably positioning the adjacent end of the spring shank 26. Positioned in slot 30 10 said shank assumes approximately the position shown in Fig. 4. Positioned in slot 31, it assumes the general form indicated by the dotted lines 15 95 of Fig. 4 thereby substantially modifying the free form of the loop shank 26, the angle of said shank and its longitudinal position, each relative to the toe piece bottom or body 23, and consequently adapting said loop to contact in a materially different form of shoe or to exert a materially different shoe-straightening pressure in 20 the first form thereof.

Said slideable reinforcing member 90 when in the position indicated by dotted line 93 tends to increase the radius of the loop shank underlying it and materially increases the resilient resistance against the compression of said loop, thereby adapting it better to the straightening of a heavier or stiffer shoe or to apply a like treeing pressure in a larger shoe. One or all of said adjustment features may be used in any tree.

30 However, I have found that with the differing shoes of one individual, it is often possible to use said tree satisfactorily without the current use of any of said adjustments, as the spring shank 26 is adapted to exert satisfactory treeing, straightening effects in considerably differing forms or weights of shoes. The latter effects are due to the considerable degree of resiliency and flexibility provided in the greatly elongated spring 35 of said shank. For detached use of the tree 40 of the socket 31 is unnecessary.

The aforesaid tree with the socket 31 attached is readily snapped into fixed or substantially rigid position on the wall rack arm 40 (see Fig. 2), after which it is generally unnecessary to touch or directly to handle the tree for its use. By its toe end, a shoe may be held in the hand in a position just above the tree, whence a single slightly forceful movement serves to push the shoe down into engaging position under straightening pressure or stress on said rigidly supported tree. A reversal of said movement will remove the shoe 50 with equal facility.

The tree is shown with a woman's shoe mounted thereon in Fig. 2 and said tree in a single size is adapted for a great majority of women's shoes. For men's shoes a tree of the same general design is provided preferably with a materially longer toe piece 21 and a more powerful long spring shank 26. The rack with its arm 40 55 may be used interchangeably for either men's or women's shoes by placing thereon the proper tree. Six shoes for women will generally fit into the same space on the rack bar 41 as is required for four shoes for men. The arms 40 are slidably positioned on said rack bar 41, also being readily removable and replaceable thereon. Therefore a rack spaced adaptably for men's shoes may be used for the same number of 60 women's shoes by placing thereon the proper tree. Or by adding two additional arms 40, and suitably spacing all arms equipped with women's trees, said rack may then carry six shoes.

70 The trees as aforesaid (see Figs. 1 to 5) are 75

equally adaptable for detached use or for readily mounting on said rack.

In a modified design illustrated in Figs. 6 and 7 the arm and toe piece are provided in a single body member 70 intended to be used preferably mounted on the rack bar 11. The use of this mounted tree is generally the same as that of the mounted tree already described (of Figs. 1 to 5). A spring shank 75 is illustrated as fixed on its upper end and is adjustable as to its form and resilient characteristics by means of its adjustably positioned lower end. The spring adjuster 90 (see Fig. 4) is usable on said shank 75 (see Fig. 6) although not there shown.

There are numerous advantages in the use of the shoetree and rack combination as herein described, among which is that a shoe may be placed thereon with as little effort as that required to place it on a convenient shelf. The rack may be attached to a door or wall, or it may conveniently be used on a floor bracket with the shoe preferably sloping at about a 45 degree angle upwards towards its toe end.

Whether used mounted or detached, the treeing device is adapted to exert a gentle transverse stress in a shoe, straightening the sole and smoothing out wrinkles in the vamp without imposing harmful and distorting stresses, such as frequently occur where a tree is used powerfully stretching the shoe lengthwise by means of stiff non-adjustable springs, or powerful toggle joints the stretching force of which is difficult to regulate.

Another advantageous and novel feature is provided in the easily curved contactors which, relative to a shoe being treed thereon are adapted to a gliding contacting motion similar in effect to that of a bob-sled with its tandem runners gliding over the snow. This bob-sled runner effect is especially useful on the toe and shank contacts for movement under pressure in each direction for the treeing or removal respectively of the shoe relative to the tree.

My preferred steel strip looped shank spring is of substantially lighter cross-section than that hitherto commonly used, and is provided with a resilient length materially in excess of the distance between the spaced points of the toe insole and the shank contact, said length being preferably at least one and one-half times said distance. A high degree of easy flexibility is thereby provided with ample strength of spring effective to straighten a shoe and to smooth out any wrinkles therein. The spring may be flexed to its loop shape without permanent distortion, and at all times, said looped spring is under initial resilient stress, with added stress when further flexed by contact in a treed shoe.

I have found by actual measurement that the treeing pressure on the rear (or shank) contact of my device may satisfactorily be from one-third to one-half of the pressure commonly exerted on the rear (or heel) contact of other treeing devices in general use. On a single size of tree and without using the adjustable features which I may provide, I have been able to tree any one shoe of an individual's set, from a light slipper to a heavy walking shoe, and in each case the shoe was held under effective treeing stress without harmful distortion of the shoe.

The spring shank 26 relative to the arm 40 diverges as it emerges from the socket 37 when not in use as illustrated in Fig. 4 where the dotted line 96 represents the adjacent side of the arm 40 when said shank 26 is mounted thereon. With

increasing treeing pressure against its underside, said shank bears up against said arm as shown in Fig. 2, said arm 40 therefore being adapted to the support of said spring 26 against treeing flexure at a plurality of points lengthwise thereon.

In its simplest form for detached use without adjustable features, my tree consists of only two parts, a slotted toe piece and a barbed spring shank attached, as compared with three or more parts in other devices. The barbs on said shank securely anchor it in a wooden toe piece by a mode of manufacture requiring neither an additional number of operations nor of parts.

In referring to the shank of a shoe, as a point of contact, I refer generally to the mid-length section inside of said shoe. Said shank or rear contact effect of my device contrasts with the generally horizontal stretching pressure exerted against the rear end wall or backstay of a shoe when treed on the toggle-jointed type of tree or the similar spring-actuated type thereof. In referring to generally "perpendicular" treeing pressure in a shoe, I mean about perpendicular relative to the tree-contacted surface thereof. In referring to pressure "downward" against the toe end, I mean downward relative to a shoe in normal position with its sole and heel on the floor; and the similar phases, "upward" against the vamp, "downward" against the shank, a "vertical" loop spring, and the like are to be similarly understood. In referring to the "body" of the tree, I may refer to the single preferably cast piece 70 (see Fig. 6) comprising a supporting arm and toe piece integrally made; or, for the tree form shown in Fig. 5 without an integral supporting arm, the term "body" may refer only to the toe piece part 21.

I have found that various modifications, substitutions and transpositions may be made in the preferred construction of my device herein set forth, and others may occur to those skilled in mechanical arts. For instance, for obtaining adjustment of the resilient characteristics, form of spring, and relative point of contact thereof in a shoe, various mechanical details including slideable levers or wedges, rotatable eccentrics and others are adaptable.

Having described a novel shoe tree, optionally in combination with supporting means, adapted for use with an ease and convenience which I have been unable to discover elsewhere, I wish to claim broadly the principles of construction pertaining thereto.

What I claim is:

1. A shoe straightening tree comprising a body; contact surfaces on said body adapted to contact downwardly against the toe insole and upward against the vamp of a treed shoe; an extending arm part of said body adapted to the generally rigid support thereof from external supporting means; and a resilient shank contact member forming generally a vertical flexible extended loop attached to said body adapted to contact against the shank of a treed shoe; said supported tree being provided in a form adapted to the treeing thereon and removal therefrom of a shoe without the manipulation of any part of said tree and support.

2. A shoe straightening tree comprising a body; contact surfaces on said body adapted to contact downward against the toe insole, and upward against the vamp of a treed shoe; an extending arm part of said body detachably connected thereto adapted to the generally rigid

- support thereof from external supporting means; and a resilient shank contact member forming generally a vertical flexible extended loop attached to said body adapted to contact against the shank of a treed shoe; said supported tree being provided in a form adapted to the treeing thereon and removal therefrom of a shoe without the manipulation of any part of said tree and support.
10. 3. A shoe straightening tree adapted to the treeing thereon and to the removal therefrom of a shoe by means of a simple generally continuous relative movement of said tree and shoe for each said operative movement; said tree having a toe insole contactor provided with a bottom surface substantially extending in both directions lengthwise from its part in contact with a treeing shoe insole; and a flexible extended loop shank contactor provided with a bottom surface substantially extended in both directions lengthwise from its part in contact with said shoe shank; all said extended parts being curved upwardly relative to the adjacent part of said shoe, and said contactors being adapted jointly to support said tree bob-sled runner fashion for a gliding movement under pressure in and relative to said shoe.
4. A shoe straightening tree comprising a body provided with contact surfaces adapted to contact downward against the toe insole and upward against the vamp of a treed shoe; a resilient flexible shank member attached to said body forming therewith generally an extending loop in a vertical plane adapted to make pressure contact downwards against the shank of said shoe; and means of adjustment of the degree of flexibility of said looped shank, including a longitudinally extending reinforcing part movably supported for adjustably positioned reinforcing contact on said resilient shank.
5. A shoe straightening tree comprising a body having a forward lower surface and a backwardly-spaced upper surface adapted respectively to contact downwards in the toe-end and upwards against the vamp of a treed shoe; and a flexible spring, adapted to exert pressure contact on the shank part of a treed shoe by means of the lower part of a rearwardly extending, approximately semi-circular flexible loop formed in said spring supported at both its forwardly extending ends by said body.
6. A shoe straightening tree comprising a body having a forward lower surface and a backwardly-spaced upper surface adapted respectively to contact downwards in the toe-end and upwards against the vamp of a treed shoe; a resilient flexible rearwardly-extending shank member adapted to contact downwards against the shank of said shoe; means whereby said extending shank member may be removably attached to said body at a predetermined angle relative thereto as viewed in side elevation; and means whereby said member may be removably attached at another differing angle, thereby providing an adjustment adapting said tree for use with a plurality of shoes respectively differing in form.
7. A shoe straightening tree comprising a body having a forward lower surface and a backwardly-spaced upper surface adapted respectively to contact downwards in the toe-end and upwards against the vamp of a treed shoe; a resilient flexible rearwardly-extending shank member adapted to contact downwards against the shank of said shoe; means whereby said extending shank member may be removably at-

tached to said body at a predetermined point in the length thereof; and means whereby said member may be removably attached at another point spaced longitudinally from first said point, thereby providing an adjustment adapting said tree for use with a plurality of shoes respectively differing in form.

8. A shoe-straightening tree comprising a body adapted to be placed in the forward end of a shoe, having a toe-end surface adapted to contact downward on the insole at the toe end of a treed shoe; a vamp surface on the top of said body near its rear end, adapted to contact upward against the vamp of a treed shoe; and a strip spring member attached at its upper forward end to said body, extending substantially rearward and curving downward and thence forward to form a resilient flexible loop adapted on its lower part to exert pressure contact generally downward against the shank of a treed shoe, the lower forward end of said member being supported by said body.

9. A mountable shoe-straightening tree comprising a body adapted to be placed in the forward end of a shoe, having a toe-end surface adapted to contact downward on the insole at the toe end of a treed shoe; a vamp surface on the top of said body near its rear end, adapted to contact upward against the vamp of a treed shoe; means on said body adapted to engage on a projecting arm for the mounted support of said tree; and a strip spring member attached at its upper forward end to said body, extending substantially rearward and curving downward and thence forward to form a resilient flexible loop adapted on its lower part to exert pressure contact generally downward against the shank of a treed shoe, the lower forward end of said member being supported by said body.

10. A mountable shoe-straightening tree comprising a body adapted to be placed in the forward end of a shoe, having a toe-end surface adapted to contact downward on the insole at the toe end of a treed shoe; a vamp surface on the top of said body near its rear end, adapted to contact upward against the vamp of a treed shoe; means on said body adapted to the removable mounting of said tree, including a resilient member adapted to lock said mounting means on a supporting arm; and a strip spring member attached at its upper forward end to said body, extending substantially rearward and curving downward and thence forward to form a resilient flexible loop adapted on its lower part to exert pressure contact generally downward against the shank of a treed shoe, the lower forward end of said member being supported by said body.

11. A mountable shoe-straightening tree comprising an extending arm adapted to engage on a supporting means; a shoe-tree body member formed on said extended arm, adapted to be placed in the forward end of a shoe, having a toe-end surface adapted to contact downward on the insole at the toe end of a treed shoe; a vamp surface on the top of said body near its rear end, adapted to contact upward against the vamp of a treed shoe; and a strip spring member attached at its upper forward end to said body, extending substantially rearward and curving downward and thence forward to form a resilient flexible loop adapted on its lower part to exert pressure contact generally downward against the shank of a treed shoe, the lower forward end of said member being supported by said body.

12. A shoetree and rack combination comprising

ing a shoetree adapted to be inserted in a shoe and therein to make resilient pressure contacts respectively and relatively downward against a shoe toe-end insole and a shank, and upward against said shoe vamp, said three contacts positioning on a generally wedge-like outline with said vamp contact in opposition to said toe and shank contacts; and a rack adapted to be mounted on a fixed support, having a diagonally upwardly extending arm adapted to the fixture thereon of said shoe tree with said toe and vamp contacts positioned generally vertically above said shank contact, whereby a treed shoe is carried with its toe end generally vertically over its heel end and the force of gravity then tends to draw down and to hold said shoe in place on said wedge-like tree.

13. A shoe-straightening tree comprising a longitudinally-extending body; contact surfaces

on said body adapted to contact downward against the toe insole and upward against the vamp of a treed shoe; means adapted to contact downward against the shank part of a treed shoe and to exert resilient pressure affecting all three said contacts; and means of adjustment whereby the force of said resilient pressure may be adjustably controlled. 5

14. A shoe-straightening tree comprising a longitudinally-extending body; contact surfaces on 10 said body adapted to contact downward against the toe insole and upward against the vamp of a treed shoe; means adapted to contact downward against the shank part of a treed shoe and to exert resilient pressure affecting all three 15 said contacts; and attached means of adjustment whereby the force of said resilient pressure may be adjustably controlled.

HUGH R. MACMICHAEL.
